ABSTRACT OF THE DISCLOSURE

A housing for a rotary piston internal combustion engine, especially of trochoidal construction, which comprises a housing case provided internally with running surfaces along which slide the piston corners, and lateral housing parts closing off the housing case in the axial direction of the engine, whereby a small groove extending substantially parallel to the running surfaces is provided in the sidewall of each housing case closely adjacent to the running surfaces. The small groove may extend over the entire circumference of the housing case or only over that portion which is considerably hotter than the rest of the housing case.

Background of the invention

The present invention relates to a housing case for a rotary piston internal combustion engine, especially for an internal combustion engine of trochoidal construction, which housing case is provided with an internal running surface for the piston and to the lateral side walls of which are secured lateral housing parts on both sides in the axial direction.

It has been noted with rotary piston internal combustion engines of trochoidal construction that the lateral housing parts deform because the housing case, which becomes very much hotter within the area of the compression chamber and of the expansion chamber than within the area of the suction chamber, expands unevenly and is distorted thereby. The greatest distortion and warping thereby occurs in the area of the running surface for the piston. The consequence thereof is a distortion of the lateral housing parts which should remain completely flat in the interest of a good oil seal.

Summary of the invention

The present invention is concerned with the aim to so construct the housing case that a non-uniform expansion thereof in proximity of the running surface cannot affect the lateral parts of the internal combustion engine housing. The underlying problem is solved in a simple manner according to the present invention in that a groove is provided in each lateral wall of the housing case closely adjacent the running surface and extending parallel thereto at least over a part or over the entire circumference.

By the arrangement of at least one groove, the edge of the housing case can deform within the area of the running surface during heating up without exerting a pressure on the lateral housing parts which might deform the same.

In an advantageous construction of the inventive concept the groove may be arranged exclusively within the hot arc of the housing case, for example, within the area between the spark plug and the exhaust channel.

Accordingly, it is an object of the present invention to provide a housing for a rotary piston internal combustion engine, especially of trochoidal construction, which is simple in construction, yet eliminates the afore-

2

mentioned drawbacks encountered with the prior art constructions in an effective manner.

Another object of the present invention resides in a housing case for rotary piston internal combustion engines which greatly improves the oil sealing properties thereof under all operating conditions.

A further object of the present invention resides in a housing for a rotary piston internal combustion engine of trochoidal construction which effectively prevents deformation and distortions of the lateral housing parts which might adversely affect the tightness of the oil seals.

These and further objects, features and advantages of the present invention will become more obvious from the following description when taken in connection with the accompanying drawing which shows, for purposes of illustration only, one embodiment in accordance with the present invention, and wherein:

FIGURE 1 is an elevational view in the axial direction on the housing case of rotary piston internal combustion engine of trochoidal construction, according to the present invention;

FIGURE 2 is a cross-sectional view through the housing case, taken along line II—II of FIGURE 1, with the lateral housing parts attached; and

FIGURE 3 is an elevational view, similar to FIGURE 1, on a modified embodiment of a housing case in accordance with the present invention.

FIGURES 4 and 5 are similar to FIGURES 1 and 2, respectively, showing two grooves.

Referring now to the drawing wherein like reference numerals are used throughout the various views to designate like parts, the housing of a rotary piston internal combustion engine of trochoidal construction according to FIGURES 1 and 2 is essentially constituted by the housing case 1 and by the two lateral housing parts 2 which are attached to the housing case 1 in the axial direction. The housing case 1 is equipped with a running surface 3 along which slides the piston of the internal combustion engine during its rotation. In the interest of a safe oil sealing between the end walls of the piston and the lateral housing walls 4 or the lateral housing parts 2, it is necessary that the lateral walls 4 remain completely flat. Hence, no distortion should occur which might be caused by the fact that the housing case 1 heats up in proximity to its running surface 3 by the operation of the internal combustion engine and presses against the side walls 4 of the lateral housing parts 2. For purposes of avoiding the distortion of the lateral walls 4, a groove 7 of rectangular cross section is provided in each side wall 5 of the housing case 1 at a peripherally small distance 6 to the running surface 3. Between each groove 7 and the running surface 3 by the lateral walls 5 of the housing case 1 a rim or edge 8 is formed which cannot transmit any large forces. This rim or edge 8 is deformed if the housing case 1 expands within the area of its running surface 3 in the axial direction so that no pressure is exerted on the lateral walls 4 of the lateral housing parts 2.

According to FIGURE 3, it suffices if the grooves 7 in the lateral walls 5 of the housing case 1 extend only within the area of the so-called hot arc 9 between a spark plug 10 and the outlet channel 11.

While I have shown and described two embodiments in accordance with the present invention, it is understood that the same is not limited thereto but is susceptible of numerous changes and modifications as known to a person skilled in the art. For example, in lieu of a single groove in each side wall of the housing case, two grooves, as shown in FIGURES 4 and 5, may possibly be provided in each wall of the case which are arranged parallel to each other and at a small distance from each other.

Thus, it is obvious that the present invention is not limited to the details shown and described herein and I therefore do not wish to be limited thereto but intend to cover all such changes and modifications as are encompassed by the scope of the appended claims.

I claim:

1. A housing case for a rotary piston internal combustion engine, especially of trochoidal construction which includes running surface means for the piston on the inside thereof, and to the lateral walls of which are attached on both sides in the axial direction lateral housing parts, wherein the improvement comprises anti-warp groove means provided in each lateral wall of the housing case closely adjacent the running surface means and approximately parallel thereto, said groove means being spaced so closely adjacent to the running surface means that edge portions are formed in the housing case incapable of transmitting large forces but capable of deformation in case of thermal expansion so as to prevent distortion and warping in the lateral walls.

2. A housing case according to claim 1, wherein the groove means extend at least partly over the circumference of the running surface means.

3. A housing case according to claim 1, wherein the groove means extend over the entire circumference of the running surface means.

4. A housing case according to claim 1, wherein the groove means is arranged exclusively within the area of the hot arc of the housing case.

5. A housing case according to claim 4, wherein said hot arc is located between the spark plug and the outlet channel.

6. A housing case according to claim 1, wherein two groove means are provided in each lateral wall which extend substantially parallel to each other.

7. A housing case according to claim 3, wherein two groove means are provided in each lateral wall which extend substantially parallel to each other.

8. A housing case according to claim 4, wherein two groove means are provided in each lateral wall which extend substantially parallel to each other.
